UNITED STATES PATENT OFFICE.

THOMAS KENNEDY, OF PHILADELPHIA, PENNSYLVANIA.

PUMP.

SPECIFICATION forming part of Letters Patent No. 331,976, dated December 8, 1885.

Application filed May 28, 1885. Serial No. 166,959. (No model.)

To all whom it may concern

Be it known that I, THOMAS KENNEDY, a citizen of the United States, residing in Philadelphia, Pennsylvania, have invented certain 5 Improvements in Pumps, of which the following is a specification.

My invention relates to a small portable hand-pump, such as is used for forcing beer and other liquids, the object of my invention 10 being to so construct such a pump and the plunger operating devices of the same, that the plunger can be readily removed from the barrel of the pump at any time without disturbing said barrel, and can be as readily in- 15 serted in the barrel again when desired.

In the accompanying drawings, Figure 1 is a side view, partly in section, of a pump with my improvements; Fig. 2, an enlarged section of the upper portion of the pump-barrel and 20 plunger, the latter being detached from the barrel, and part of the plunger-rod being shown in elevation; and Fig. 3, a section on the line 1 2, Fig. 1, also on a larger scale than said figure.

25 A is the base, to the rear of which is secured a flanged plate, B', at the lower end to a curved standard, B, the upper front end of the latter having a detachable plate, D, secured thereto by means of a bolt, a, the stem of 30 which passes through a slot, b, in the plate, and is furnished with a thumb-nut, d, bearing on said plate. In the outer portion of the plate is an opening forming a guide for the plunger-rod F of the pump which has at the 35 lower end the usual plunger, G, adapted to the barrel H of the pump, a flange at the base of said barrel being secured by bolts f to the base A near the front end of the same. An operating-lever, J, is connected by a transverse 40 bolt, g, to the plunger-rod F, this lever being hung to a pair of links, K, which are pivoted to a stud, h, on the standard B. The lever J is connected to the links K by means of a transverse bolt, m, to the threaded end of 45 which is adapted a thumb-nut, n, as shown in Fig. 3.

When it is desired to examine or repair the plunger of the pump, or to gain access to the interior of the barrel H, the thumb-nuts d and 50 n are removed, thus permitting the withdrawal of the bolts a and m, and thereby freeing the

lever J from the control of the links K, and permitting the removal of the guide-plate D from the standard B, the lever and plunger-rod being then lifted, so as to withdraw the 55 plunger from the barrel of the pump, the top p of which is detachable for the purpose of permitting such withdrawal.

After the examination or repairs have been completed the plunger can be again inserted 60 into the barrel, the parts restored to their former position, and the thumb-nuts d and n reapplied.

The slotting of the guide-plate D for the reception of the confining-bolt a is important, as 65 it permits the adjustment of said guide-plate in respect to the standard B, which adjustment is rendered necessary by the fact that the standards are liable to vary in size and shape, owing to inequality in the shrinkage 70 of the castings, and this, if the guide was not adjustable, would have a tendency to throw said guide out of line with the plunger-rod, it being understood that the seats formed on the base A for the reception of the pump-barrel 75 and standard occupy a fixed relation to each other.

The plunger of the pump consists of a cupped washer, s, of leather, rubber, or like flexible material clamped between a cap-plate, 80 t, and an internal notched spring-plate, w.

When the plunger is withdrawn from the barrel of the pump, the lower end of the washer s is expanded, so that its diameter is greater than the internal diameter of the barrel; hence 85 difficulty would be experienced in inserting the plunger into the barrel of the pump in the absence of some provision for contracting the lower end of said washer, so that it will freely enter the barrel. This I accomplish by providing the barrel with a flaring top, x, the upper portion of which has an internal diameter greater than the external diameter of the expanded lower end of the washer s, as shown in Fig. 2, said top terminating below in an internal rib, y, the diameter of which is slightly less than that of the barrel of the pump. It will thus be seen that when the plunger is thrust down into the top of the barrel, the lower end of the washer s will be automatically contracted to such an extent that it will freely 95 enter the barrel.

The flaring mouth and contracted internal rib, *y*, may be made by properly bending or swaging the metal of which the barrel of the pump is composed; but I prefer, for convenience, to provide said barrel with a separate mouth-piece, as shown.

Various modifications in the means of pivoting the lever *J* may be adopted without departing from my invention. For instance, a single link may be used instead of two links, as shown, and the pivot whereby the lever is hung to the link or links may be secured to said lever or to the links, the bolt whereby the hanging of the link or links to the stud *h* is effected, being removable, and thumb-screws may, as will be evident, be substituted for the bolts with thumb-nuts.

In some cases it may be sufficient to have the guide-plate *D* alone detachable, but it is preferred to make both the same and the operating-lever detachable for greater convenience.

I claim as my invention—

1. The combination of the base *A*, the pump-barrel *H*, and curved standard *B*, seated on and secured to said base, the plunger and plunger-rod, and the guide *D*, for the latter, said guide having a slotted connection with the upper end of the curved standard, so as to be adjustable in respect thereto, as set forth. 25

2. The combination of the plunger of the pump, having a flexible washer, with the pump-barrel having a flaring mouth, and an internal rib less in diameter than the barrel, as specified. 30

In testimony whereof I have signed my name to this specification in the presence of two subscribing witnesses.

THOS. KENNEDY.
